UNITED STATES PATENT OFFICE.

ALONZO AFFERD MASSIE, OF PHILADELPHIA, PENNSYLVANIA.

BARBER'S CABINET.

Application filed November 29, 1921. Serial No. 518,689.

To all whom it may concern:

Be it known that I, ALONZO A. MASSIE, a citizen of the United States, residing at Philadelphia, in the county of Philadelphia and State of Pennsylvania, have invented a new and useful Barber's Cabinet, of which the following is a specification.

This invention relates to toilet cabinets, the primary object of the invention being to provide a cabinet which will conveniently carry and hold the necessary articles for shaving purposes.

Another object of the invention is to provide a novel form of support positioned within the central or body portion of the cabinet, for supporting a mirror, shaving brush, and shaving mug.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view of the cabinet in its closed position.

Figure 2 is a side elevational view of the same.

Figure 3 is a front elevational view of the cabinet, showing the same in an opened position.

Referring to the drawings in detail, the reference character 5 designates the base of the cabinet which is provided with suitable openings to accommodate the slidable drawers 6 which may be employed for containing various articles.

The body portion of the cabinet embodies a rear section 7 which is secured to the base, and as shown is provided with a compartment 8 to accommodate relatively small articles such as pins or the like. The side walls of the cabinet are indicated at 9 and 10 respectively, each of the side walls being hinged to the rear section 7 as by means of the hinges 11. Each of the side walls carries a right angled section 12 which are stationary, with respect to the side walls, and these sections 12 form the front or forward portion of the cabinet, there being pro-

vided suitable knobs indicated at 13 by means of which the cabinet may be opened to gain access to the interior thereof.

Forming a part of the cabinet is a sectional top the section 14 being carried by the rear section 7 while the sections 15 are carried by the side walls 9 and 10.

A support indicated at 16 is positioned on the base 5 and embodies an upper circular portion 17 designed to accommodate a mirror 18, lateral arms 19 and 20 being provided intermediate the length of the support for accommodating various articles such as a shaving brush or shaving mug. A suitable support 21 is also provided on the support 16, which support 21 may be designed to accommodate any article such as powder or the like.

Pockets 22 are provided by each of the side walls 9 and 10, which pockets may support powder, shaving stick or the like. A tooth brush holder 23 is carried by the wall 9 and embodies a pair of retaining bands.

From the foregoing it will be seen that by moving the walls 9 and 10 to positions as indicated by Figure 3 of the drawings, the articles necessary to complete the toilet are in easy access of the user.

Having thus described the invention, what is claimed as new is:

In a cabinet, a base, a rear section secured to the base and having an upwardly inclined top section formed with angular edges, side sections hingedly connected to the rear section, said side sections having top sections, each of the top sections being inclined upwardly, the inner edges of the top sections being disposed at angles to closely engage the angular edges of the top section of the rear section, a right angled wall forming a part of each side section, said right angled walls adapted to cooperate to provide the front wall of the cabinet, and the upper edges of the right angled walls being inclined to provide a continuation of the top sections of the side sections.

In testimony that I claim the foregoing as my own, I have hereto affixed my signature in the presence of two witnesses.

ALONZO AFFERD MASSIE.

Witnesses:

CURTIS MASSIE,
Rev. JOHN T. ROBINSON.
